TOY TOMAHAWK

Joseph Foster Otto, Weidman, Mich.

Application February 17, 1955, Serial No. 34,556

Term of patent 7 years

(Cl. D34—15)

Fig. 3

Fig. 1

Fig. 2

Fig. 1 is a side elevational view of a toy tomahawk, showing my new design, the opposite side having substantially the same appearance;

Fig. 2 is an end elevational view thereof; and

Fig. 3 is a top plan view thereof.

The drawing figures are stippled to indicate color contrast.

This application is a continuation-in-part of my co-pending application Serial No. D. 22,216 filed November 10, 1952, now abandoned.

I claim:

The ornamental design for a toy tomahawk, substantially as shown and described.
